(57) **CLAIM**

The ornamental design for an extension cord plug and receptacle, as shown and described.

DESCRIPTION

FIG. 1 is a front, top perspective view of an extension cord plug and receptacle, showing my new design;

FIG. 2 is a rear, bottom perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof;

FIG. 8 is a bottom plan view thereof; and,

FIG. 9 is a cross-sectional view taken in the direction of line 9-9 referenced in FIG. 7.

The dash-dash broken lines depict portions of the extension cord plug and receptacle that form no part of the claimed design. The dash-dot-dot-dash broken lines denote the boundaries of the enlarged detail views and the symbolic break which form no part of the claimed design. The extension cord plug and receptacle is shown with a symbolic break in its length. The appearance of any portion of the extension cord plug and receptacle between the break lines forms no part of the claimed design.
